US00D568855S

(12) **United States Design Patent** (10) **Patent No.:** **US D568,855 S**
Wang (45) **Date of Patent:** **** May 13, 2008**

(54) **MOBILE PHONE**

(75) Inventor: **Hung-Tse Wang**, Yunlin Shien (TW)

(73) Assignee: **Quanta Computer Inc.**, Kuei Shan Hsiang, Taoyuan Hsien (TW)

(**) Term: **14 Years**

(21) Appl. No.: **29/261,699**

(22) Filed: **Jun. 19, 2006**

(51) **LOC (8) Cl.** **14-03**

(52) **U.S. Cl.** **D14/138**

(58) **Field of Classification Search** D14/138, D14/496, 341-347; 455/575.3, 575.1; D21/517
See application file for complete search history.
